TRAIN MESSAGE DELIVERY FORK

Emil G. Grams, Willmar, Minn.

Application May 24, 1950, Serial No. 163,990

9 Claims. (Cl. 258—3)

1

My invention relates to devices for delivering messages to moving vehicles and, more particularly, to train order delivery devices often referred to as train order hoops or forks.

Frequently, due to heavy loads or steep grades, it is necessary or desirable to successively attach a pair of locomotives or engines to a train. Under such circumstances, a problem arises when it is desired to pass messages to the engineer of each of the engines. This is true because of the fact that the engineer in each engine is normally located the same distance from the ground and in view of the further fact that two such successively-coupled engines pass a given point so rapidly that it is extremely difficult, if not impossible, to reload the conventional message delivery fork in time for delivery of a message to the second engine.

The primary object of my invention is the provision of simple and inexpensive means whereby identical messages may be passed from a single message-delivering fork in rapid succession.

A still further object of my invention is the provision of means whereby the second message is automatically placed in delivering position by delivery of the first message.

A still further object of my invention is the provision of a simple and inexpensive reloading attachment for the above purpose, which may be readily secured to and removed from a conventional train order delivery fork or hoop.

The above and still further objects and advantages of my novel structure will become apparent from the following detailed specification, appended claims, and attached drawings.

Referring to the drawings, wherein like characters indicate like parts throughout the several views:

Fig. 1 is a front elevation of my novel structure loaded for delivery of two messages;

Fig. 2 is a view corresponding to Fig. 1 but showing a different position of some of the parts, due to delivery of the first message;

Fig. 3 is an enlarged fragmentary view in side elevation taken on the line 3—3 of Fig. 2; and

Fig. 4 is an enlarged view in side elevation taken substantially on the line 4—4 of Fig. 2.

Referring with greater particularity to the drawings, the numeral 1 indicates, in its entirety, the conventional train order fork including a generally upright supporting member or shank 2 adapted to be either manually or mechanically supported by means not shown. An enlarged head 3 is rigidly secured to the upper end of the supporting shank 2 and forms an extension 50

2

thereof. A pair of rigid diverging arms project upwardly from the head 3 in a common plane. The head 3, intermediate the arms 4, is provided, preferably on an opposite side, with upwardly-opening clips 5, preferably in the nature of a spring steel tongue riveted as at 6 to the metal casing 7 forming the head 3.

By reference particularly to Fig. 3, it will be observed that the arms 4, at their upper ends, are provided with laterally-extending aligned notches 8. As shown in Fig. 1, the notches 8 cooperate with the spring clips 5 to releasably support an endless message-holding element or cord 9. Cord 9 is, preferably and as shown, provided with a loop 10 into which a message 11 is adapted to be received. Either of the spring clips 5 may be utilized. However, it is desirable that the clip into which the cord 9 has been secured be positioned to face the on-coming train to which the message 11 is to be delivered.

Up to this point, I have described only a conventional type of train order delivery fork. My invention relates to a novel reloading device for structures of the above type and comprises a second pair of diverging arms 12, each of which is provided at its upper ends with a laterally-projecting closed loop 13 adapted to slidably receive therein one of the rigid arms 4. Preferably and as shown, the arms 12 are formed from a single length of resilient steel wire, each thereof adjacent their lower ends being formed to provide a torsion spring 14. At their lower ends, the arms 12 are formed to provide a laterally-extended loop 15 which receives therein the supporting shank 2.

It is important to note that the arms 12, by virtue of their own resiliency plus the resiliency of the torsion springs 14, are yieldingly biased to spread their free upper ends apart a distance at least equal to that of the space between the upper ends of the arms 4, and preferably even a greater distance. This factor is extremely important in the operation of my device, as will hereinafter become apparent, for the arms 12, by camming action of the loops 13 upon the rigid arms 4, will automatically rise from the position of Fig. 1 to the side-by-side relationship of Fig. 2.

Projecting laterally from the upper ends of the arms 12 in a direction opposite to the loops 13 are a pair of friction clips 16 which may, as shown, be formed integrally with the loops 13, that is, from a single length of wire. A frictional clip 17, preferably and as shown formed from a length of resilient stock bent backwardly upon itself, is

pivotal secured as at 18 to the looped upper end of a supporting arm 19. The lower end of the supporting arm 19 is wound tightly about the lower abutting ends of the arms 12 adjacent the loop 15, as indicated at 20, so as to impart permanence to the loop 15.

When it is desired to utilize my novel automatic message-reloading device, the message-holding cord 9 is positioned, as indicated in Fig. 1, with the message 11 preferably intermediate the free ends of the arms 4. In this position, the cord 9 is received within the notches 8 and in one of the spring clips 5. Thereafter, a second endless message-delivering cord 21, having a message-receiving loop 22 therein, is inserted 10 between the laterally-opening friction clips 16 and the friction clip 17. It will be noted that the message 23, in the loop 22, is positioned along one side of the triangle instead of between the free ends of the arms 12. Finally, 20 the portion of the cord 21 intermediate the free ends of the arms 12 is pulled downwardly until the arms 12 have assumed the position of Fig. 1. At this point, the cord 21 is forced into the same clip 5 into which the cord 9 has been forced, as there shown. It will be noted that the cord 21 is immediately above the cord 9 and removal of the cord 9 must necessarily remove the cord 21. The device is now placed in position, whereby the cord 9 may be intercepted by personnel aboard the first engine of an on-coming train.

As above indicated, when the cord 9 is removed in the conventional manner, the cord 21 is freed from the spring clip 5. The free 30 ends of the arms 12 are thereafter free to expand. Consequently, the arms 12 and loop 15 will clamp respectively upon the rigid arms 4 and shank 2 to the position of Fig. 2. This change of positions is almost instantaneous. Therefore, irrespective of the speed of the train, the second message delivery cord 21 will be in a position to be intercepted by the second engine in ample time.

My device has been thoroughly tested and found to be completely satisfactory for the accomplishment of the above objects; and, while I have disclosed a preferred embodiment of my invention, it should be obvious that the same is capable of considerable modification without departure from the spirit and scope of the appended claims.

What I claim is:

1. A device for delivering messages to a moving vehicle, said device comprising a generally upright supporting member, a pair of relatively rigid arms diverging upwardly from the upper end of said supporting member, means on said arms and member for holding an endless flexible message-carrying element, said means including a friction clip on said member, a pair of upwardly-diverging resilient arms, a means mounting said second pair of arms on said supporting member for sliding movements longitudinally of said member toward and away from side-by-side relationship, and clip means on the opposite ends of said second arms for releasably supporting a second flexible message-holding element.

2. A device for delivering messages to a moving vehicle, said device comprising a generally upright supporting member, a pair of rigid arms diverging upwardly from the upper end of said supporting member, means on said arms and member for holding an endless flex-

ible message-carrying element, said means including a friction clip on said member, a second pair of upwardly-diverging arms, said arms being yieldingly biased to spread their free upper ends apart a distance at least equal to a distance between the upper ends of said rigid arms, means mounting the upper ends of said second arms one each to one of said rigid arms for sliding movements longitudinally thereof, means mounting the lower end portions of said arms to said supporting member for longitudinal sliding movements thereon, and clip means associated with the opposite ends of said second arms cooperating with the clip on said support to releasably support a second endless flexible message-holding element, the bias of said second arms hinging the same toward side-by-side relationship, one each with one of said rigid arms.

3. A device for delivering messages to a moving vehicle, said device comprising a generally upright supporting member, a pair of rigid arms diverging upwardly from the upper end of said supporting member, means on said arms and member for holding an endless flexible message-carrying element, said means including a friction clip on said member, a second pair of upwardly-diverging arms, means mounting the upper ends of said second arms one each to one of said rigid arms for sliding movement longitudinally thereof, means mounting the lower end portions of said arms to said supporting member for longitudinal sliding movements thereon, yielding means biasing said second arms toward a spread-apart relationship of their upper ends and causing said second arms to be normally disposed in side-by-side relationship one each with one of said rigid arms, and clip means associated with opposite ends of said second arms cooperating with the clip on said support to releasably support a second endless flexible message-holding element, said yielding means urging said second arms toward side-by-side relationship, one each with one of said rigid arms.

4. The structure defined in claim 2 in which said second pair of arms are formed from a single length of resilient wire, said wire being formed at its intermediate portion to provide a bearing-forming loop around said supporting member.

5. The structure defined in claim 2 in which said second pair of arms are formed from a single length of resilient wire, said wire being formed at its intermediate portion to provide a bearing-forming loop around said supporting member and a pair of torsion springs one each associated with one of said second arms.

6. An accessory for use on devices for delivering messages to moving vehicles, said devices including a generally upright supporting member, a pair of rigid arms diverging upwardly from the upper end of said supporting member, and means including an upwardly-opening friction clip on said supporting member adjacent the upper end thereof for holding an endless flexible message-carrying element, said accessory comprising a bearing element adapted to be slidably received on said supporting member for longitudinal sliding movements with respect thereto, a pair of arms associated with said bearing element and projecting generally upwardly and outwardly therefrom, means yieldingly biasing said second arms and said bearing element in an upward direction, where-

by to position said second arms in a side-by-side relationship with said first-mentioned arms, and clip means on the opposite ends of said second arms for holding a second endless flexible message-carrying element thereon.

7. The structure defined in claim 6 in which said arms and bearing element are formed from a single length of resilient wire.

8. The structure defined in claim 6 in which said element and arms are formed from a single length of flexible wire and in which a portion of said yielding means comprises integrally-formed torsion springs on said arms adjacent said bearing.

9. The structure defined in claim 6 in which the clip means on the opposite ends of said last-mentioned arms comprises laterally out-

wardly-opening clips on the outer ends of said second arms, and a clip mounted adjacent the lower end portions of said second arms, said last-mentioned clip being movable about a horizontal axis whereby to open upwardly or laterally outwardly.
